Aldo Rommelle
ATTORNEY

UNITED STATES PATENT OFFICE.

JOSEPH H. SANDERSON, OF BABYLON, NEW YORK.

CIGAR CASE.

Application filed March 28, 1922. Serial No. 547,367.

To all whom it may concern:

Be it known that I, JOSEPH H. SANDERSON, a citizen of the United States, and resident of Babylon, in the county of Suffolk and State of New York, have invented certain new and useful Improvements in a Cigar Case, of which the following is a specification.

This invention relates to a cigar case. Its object is the production of such a case by means of which a cigar can be adjustably suspended and separated from the walls of the case. A second object of the invention is the production of a case, in which a lighted cigar can be suspended, so that neither the lighted end or the moistened end of the cigar contacts with the walls of the case. A third object of the invention is the production of a case with appurtenances that will prevent any movement of the cigar after the case is closed. A fourth object is the production of a case having a nose end, so that it can be easily inserted into a pocket of a garment. A fifth object is the production of a cigar case, which will maintain the lighted end of a cigar spaced from the walls of the case to prevent the heating and the burning of the latter. A sixth object is the production of such a case that can be easily closed or opened, and when closed will smother the burning end of a cigar contained therein.

A seventh object of the invention is the production of a case which provides an air space all about and around a cigar suspended therein.

An eighth object of the invention is the production of a case for a cigar which can be easily cleaned of any ashes, that may separate from the lighted cigar.

A ninth object of the invention is the production of a case, in which cigars of different diameters and shapes can be easily suspended.

A tenth object of the invention is the production of a case, in which various other objects can be suspended, in spaced relation with the walls thereof.

In the accompanying drawings, Fig. 1 represents a side elevation of the case with its members locked to each other; Fig. 2 shows an inside plan view of the case when opened; Fig. 3 shows an enlarged section of Fig. 2 on the line 3, 3 with the members of the case locked to each other and Fig. 4

shows a similar section on the broken line 4, 4.

The cigar case is shown with an elongated cup shaped bottom member A, to which is hinged an elongated cup shaped top member B, by means of the hinge 20. The two members when locked together form a cigar shaped case.

The top member B is pressed in at its lower edge to form the clamping ledge 21, which provides a seat 22 for the accompanying edge 23 of the bottom member A, when the members are in their locked position. The member A has the round nose end 25, and the member B has the corresponding round nose end 26.

A spring latch 30 has one end riveted to the member A, by means of the rivet 31 and its other end 32 extends through an opening 33 in the member B, when the said members are locked to each other. To provide clearance for the latch 30 the ledge 21 is cut away for the width of the latch as indicated in Fig. 4. The member A is pressed in as indicated at 35, to prevent the head of the rivet 31 protruding from the outer face of the said member A.

A flexible tray in the member A is indicated in its entirety by the letter C, and a similar flexible tray in the member B is indicated in its entirety by the letter D.

The tray C comprises the plurality of flexible semi-circular arms 36, with the diverging outer ends 37. Longitudinal curved braces 38 with the peaks 39 connect the arms 36. The peaks 39 are fastened to the inner face of the member A, near one edge thereof, and in this instance adjacent to the hinge 20, by means of the rivets 40. By this means the arms 36 are spaced from the inner face of said member A, to provide the clearance space E. The wall of the member A is indented at 41 to provide a seat for the rivets 40, that fasten the peaks 39 to the member A.

The member D comprises the arms 36^a similar to 36, braces 38^a similar to 38. The peaks 39^a of the braces 38^a are fastened to the member B by means of rivets 40^a, the outer heads of the latter rivets being seated in indentations 41^a similar to 41. The indentations 41 and 41^a prevent the heads of the rivets 40 and 41 from protruding beyond the outer faces of the members of the case, and thereby provide a smooth surface for the latter.

To use the case it is opened as shown in Fig. 2 and a lighted or unlighted cigar is placed on the tray C, after which the member B is locked to the member A and the tray D will bear down on the cigar. The said cigar will thereby be clamped in place spaced from the walls of the case. When the case is closed the cigar, if lighted, will be extinguished. The case can now be easily inserted into a pocket of a garment without danger of any injury to the garment or the cigar.

If the cigar is to be taken from the case it is opened by pressing on the outer end 32 of the latch 30, when the members of the case can be easily unlocked and the cigar lifted from the case. The flexibility of the trays C and D permits cigars or other similar shaped objects of various diameters and shapes to be securely clamped between them.

Having described my invention what I desire to secure by Letters Patent and claim is:

1. In a case the combination of a cup shaped bottom member, a cup shaped top member hinged to the bottom member, a flexible tray for each of the members, each tray comprising a plurality of semi-circular arms, braces connected to said arms and means to fasten the braces to their respective cup shaped members.

2. In a case of the character described the combination of a cup shaped bottom member, a cup shaped top member hinged to the bottom member, a flexible tray for each of the members, each tray comprising a plu-

rality of semi-circular arms, curved braces connecting the arms of each tray, said braces having each a peak formed therewith, means to fasten the peaks to the walls of the members, the said braces formed to support the arms in spaced relation to the walls of the members of the case.

3. In a case the combination of a cup shaped bottom member with indentations in the walls thereof, a cup shaped top member with indentations in the wall thereof and also having an opening, the top member having a clamping ledge, said top member hinged to the bottom member and said ledge locking with the edge of the bottom member, a flexible tray for each of the members, each tray comprising a plurality of semi-circular arms, braces connecting the arms of each tray, rivets securing said braces to the walls of the members of the case, the outer heads of each of said rivets seated in one of said indentations, the said braces suspending said trays in spaced relation to the walls of the members to produce a clearance space between each tray and its respective member of the case, a latch with one end fastened to the member of the case by means of a rivet, the outer head of the latter rivet seated in an indentation of the bottom member and the other end of the latch detachably locking with the opening in the top member.

Signed at Babylon, in the county of Suffolk and State of New York, this 9th day of March A. D. 1922.

JOSEPH H. SANDERSON.
